UNITED STATES PATENT OFFICE

ERNEST M. ORKIN, OF NEW YORK, N. Y., ASSIGNOR TO WILLIAM WILLHEIM CO., INC.,
OF NEW YORK, N. Y.

DESIGN FOR A TEXTILE FABRIC OR SIMILAR ARTICLE

Application filed September 30, 1932. Serial No. 45,169. Term of patent 3½ years.

To all whom it may concern:

Be it known that I, ERNEST M. ORKIN, a citizen of the United States of America, residing at 10 West 86 Street, New York, N. Y., have invented a new, original, and ornamental Design for a Textile Fabric or Similar Article, of which the following is a specification, reference being had to the accompanying drawing, forming a part thereof.

The figure is a plan view of a textile fabric showing the complete width of my new design. The area within the dot and dash lines AB and CD represents one complete unit of the design, which unit is repeated in regular succession as indicated by the extensions beyond the unit boundaries. The portion of the drawing below center line EF

shows one half of the design in detail, the other portion indicated in dotted lines being a repetition of the detailed illustrations arranged in opposite relation thereto except for the border which is shown in full lines. The area GHKL represents in detail a portion of the background "M", the other portions of which are indicated by the full lines "N". The drawing is lined to indicate shading.

I claim:

The ornamental design for a textile fabric or similar article as shown and described.

In testimony whereof I have signed this specification,

ERNEST M. ORKIN,
